COLLAPSIBLE BABY OR DOLL CRIB

William L. Jago, Fremont, Ohio

Application June 28, 1941, Serial No. 400,301

1 Claim. (Cl. 5—99)

This invention relates to cradles or cribs and an object of the invention is to provide a cradle or crib which is collapsible and which may be used to accommodate either a baby or a doll.

More particularly the object of the invention is to improve upon such cribs or cradles as are now generally used and which are collapsible so as to be readily set up for use either in the home or within an automobile body.

In accordance with the present invention there is provided a collapsible crib or cradle that is characterized by simplicity of construction, combination and arrangement and number of parts, and which when folded will require but little storage space and/or effort in carrying the same about.

The invention together with its objects and advantages will be best understood from a study of the following description taken in connection with the accompanying drawings wherein:

Figure 1 is a side elevational view of the cradle or crib set up for use.

Figure 2 is a top plan view thereof.

Figure 3 is an end elevational view thereof, and

Figure 4 is a horizontal sectional view taken substantially on the line 4—4 of Figure 1.

Referring more in detail to the drawings it will be seen that in accordance with the present invention there are provided opposed standards 5—5 which may be made of wood or other suitable material and are equipped with feet or bases 6—6.

The standards or posts 5—5 are connected together through the medium of a spreader bar 7.

The bar 7 is composed of a pair of sections 8, 9 hinged together at one end through the medium of a hinge 10.

The sections 8 and 9 are hinged to the posts 5—5 through the medium of hinge straps 11—11.

The straps 11 are riveted or otherwise secured as at 12 to the free ends of the sections 8 and 9 and are provided with eyes 13—13 that are accommodated within openings 14 provided in the posts or standards 5 to cooperate with hinge pins 15 secured on the standards within said openings 14.

The sections 8 and 9 of the spreader bar 8 are secured in rigid alignment through the medium of a latch plate 16 disposed at the sides of the sections 8 and 9 opposite to the hinge 10 and pivoted at one end to, for example, the section 9 as at 17.

Rising from the section 8 is a stud 18 with which the notched end 19 of the latch bar 16 is

engageable, and is held in engagement with the stud through the medium of a wing nut 20 threaded on the stud as shown.

For the spreader bar 7 there are provided 5 braces 21—21.

The braces 21 at one end thereof are formed to straddle the sections 8 and 9 of the spreader bar 7, and said forked ends are respectively pivoted to the spreader bar sections 8 and 9 as at 22—22 by means of bolts and wing nuts to release the braces for folding the spreader bar.

Curved hinge straps 23—23 are riveted or otherwise secured at one end thereof to the brace bars 21 and have eye-equipped ends 24 engaging hinge pins 25 provided therefor on the posts 5—5 within openings 14' provided in the posts 5 adjacent the lower or base-equipped ends thereof.

The cradle basket is indicated by the reference numeral 26 and embodies a frame divided transversely into complementary half-sections 27—27 that, at opposite sides of the frame, are hinged together as at 28; together with a flexible body 26' secured to the frame sections 27—27 in any suitable manner.

At opposite ends of the basket 26 there are provided handles 29—29, and hooks 30 are provided on the standards 5 adjacent the upper ends thereof to receive the handles 29 in the manner shown in the drawings for suspending the basket 26 between said standards as shown.

Also the standards 5—5 adjacent the upper ends thereof are provided with cross-arms 31 which serve as handles through the medium of which the entire structure may be bodily handled in moving the same from one location to another, as for example in placing the structure, set up for use, into an automobile or in removing the cradle or crib from the automobile without disturbing the occupant of the basket 26.

It will also be understood that the device may be constructed in various sizes depending upon whether it is to be used for practical purposes, or as a toy.

It will also be apparent that the basket 27 may be readily removed from suspended position between the standards 5—5; the latch plate 16 swung out of engagement with the keeper stud 18, and the entire frame structure of the device then folded into a compact unit for transportation or storage purposes.

It is believed that the many advantages of a cradle or crib embodying the features of the present invention will be apparent to those skilled in the art without further detailed description.

While I have herein illustrated and described

what is considered the preferred embodiment of the invention, I am well aware that in practical fields the details of construction as herein set forth may necessitate alterations falling within the scope of what is claimed.

Having thus described the invention what is claimed as new is:

In a crib supporting structure, a pair of opposed standards adapted for supporting a crib therebetween, a spreader bar composed of two hingedly connected sections, said standards having upper and lower openings therein, horizontal pins in the openings, hinge members pivoted on said pins in the upper openings and connecting the free ends of said sections of the spreader bar

10

15

with said standards, a latch plate bridging the connected ends of said sections to secure the same in a rigid position, brace members pivoted at one end thereof to the sections of said spreader bar at opposite sides of the hinge joint between said sections, and hinge members pivoted on the pins in the lower openings and connecting the free ends of said brace bars with said standards adjacent the lower ends of the latter, said hinge members resting on the edge of their respective openings to limit downward movement of the spreader bar sections and the brace members.

WILLIAM L. JAGO.
